UNITED STATES PATENT OFFICE

2,371,205

COILED FILAMENT OR CATHODE AND
METHOD OF MANUFACTUREWilliam P. Zabel, East Cleveland, Ohio, assignor to
General Electric Company, a corporation of
New York

Application October 30, 1943, Serial No. 508,312

12 Claims. (Cl. 176—40)

This invention relates to coil structures for electric lamps and discharge devices, and especially to electric discharge electrodes, including cathodes suitable for fluorescent lamps or other tubes of low pressure positive column discharge type. The invention is hereinafter explained with particular reference to coils of refractory metal for use as fluorescent lamp cathodes, although it may also be found useful for filaments of incandescent electric lamps.

It is desirable that a fluorescent lamp cathode should heat up and become fully emissive very quickly. On the other hand, it is also desirable that the active cathode surface should all be at potentials within a restricted range during operation, if not at substantially the same potential. When the cathode is of the activated type (embodiment an electron-emissive material of low work function, as distinguished from bare metal), it is desirable that the cathode should hold and retain a plentiful supply of activating material or oxide, such as a mixture of alkaline earth metal oxides including those of barium and strontium. In addition, it is desirable that the metal structure of the cathode should present prominences or points from which the discharge can take off readily.

In the effort to meet these requirements, some rather complicated and expensive cathode constructions have been proposed, such, for example, as a coiled coil or even a triple coil; or a coiled coil with an overwind of finer wire, which may either hug the main wire or surround it loosely. However, I have now devised a coil construction which meets the requirements without necessity for multiple coiling of any component—though a coiled coil might, indeed, be embodied in it, if found desirable. Accordingly, my coil is much simpler, easier, and more economical to make than the complex structures above referred to, and can be made on ordinary, standard coiling machines. The invention affords the further advantage that in suitable forms of construction it gives a cathode which is adapted either for cold starting, or for hot starting with preheating by preliminary current flow through the cathode. The coils may be made of any metals suitable for the conditions of use, including even metals or alloys that might not ordinarily be considered refractory—such as nichrome, for example. Amongst refractory metals, tungsten and molybdenum, which I term tungsten metals, may be preferred for cathode coils that are activated with alkaline earth oxides, while tantalum may be preferred for cathode coils that are used bare and

unactivated, because of its relatively low work function.

In the forms of cathode here illustrated and described, there is a coil of main conductor wire associated with other wire that is coiled substantially coaxially and co-ordinately with the main wire, so as to intervene between its convolutions. Thus the wires co-operate to form a tubular open-work basket or grille for holding electron-emissive activating material. The size of the main conductor wire may be chosen primarily with reference to the current to be carried, and that of the other wire to assure rapid heating thereof by the discharge—though of course both wires must be taken into account in determining the electrical resistance of the cathode. If desired, the main coil may be a double or other multiple coil of several parallel wound wires, and the other coil may likewise be a multiple one; but in general the desired stiffness, resistance, and other characteristics can be obtained without the complication of multiple coils.

When coiled in the same helical sense (i. e., both as right-hand helices, or vice versa), the main and associated wires may be wound to difference pitches so as to give a criss-crossing of these wires. But in general, opposite coiling of these wires is preferable. Such a grillage holds the activating material very effectively and securely; it offers many crevices with strong capillary attraction for retaining this material against repeated or continual positive ion bombardment; and the interlocking wires coact and hold together in a thoroughly unified structure. If desired, one or more additional windings of fine wire might be successively wound on over the first fine wire winding, thus increasing the closeness of the basket or grid texture.

Various other features and advantages of the invention will appear from the description of species and forms of embodiment and from the drawing.

In the drawing,

Figs. 1 and 2 are somewhat diagrammatic fragmentary side views illustrating the winding of the several associated wires on a mandrel to form a cathode coil suitable for the purposes of the invention, and Fig. 3 is a longitudinal sectional view of the resulting coil, after heat treatment and removal of the mandrel.

Fig. 4 is a side view of the coil after mounting as part of a fluorescent lamp cathode mount, but before impregnation with activating material; and Fig. 5 is a fragmentary side view of the impregnated coil on a larger scale.

Fig. 6 is a view similar to Fig. 2 illustrating a somewhat different winding of the component wires of a cathode coil; and Figs. 7 to 10 are similar views illustrating still different windings.

All the figures are drawn much larger than the actual coils as they would be made for the cathodes of ordinary fluorescent lamps.

Figs. 1 and 2 illustrate the fabrication of a form of my cathode coil according to a preferred method which I have found convenient and economical as compared with prior methods involving multiple coiling. As shown in Fig. 1, a main conductor wire is first wound into a helix 11 on a mandrel wire M of suitable metal and size, with its adjacent convolutions suitably separated. Thereafter, another wire of smaller gauge is wound under tension on the same mandrel M into a helix 12 of opposite pitch: i. e., if the helix 11 is a left-hand one, the helix 12 is a right-hand one, or vice versa. Accordingly, convolutions of wire 12 lie against the mandrel M between those of wire 11 and cross the latter in bends outside of and conformable to wire 11. The windings may be applied to long lengths of mandrel wire by standard coiling machines used in the manufacture of coiled filaments for incandescent lamps. As shown, the pitch of the right-hand helix 12 is considerably less than that of the left-hand helix 11, being only about one-third as great. Accordingly, there are three times as many turns of the wire 12 as of the wire 11. As shown in Fig. 2, a couple of turns or convolutions of the helix 12 are seen to lie between adjacent turns or convolutions of the helix 11 in front of the mandrel M, while another turn 12 is seen crossing each turn 11. Thus the helix 12 is distorted by an outward displacement of the finer wire at each crossing 15 that it makes over the helix 11, and is, as it were, interlocked with the helix 11 against relative displacement. Of course the crossings of wire 11 by wire 12 behind the mandrel M do not appear in Fig. 2. But as the windings 11, 12 are oppositely wound and continuous, each convolution 12 must cross a convolution 11 once, and each convolution 11 is crossed by three convolutions 12.

After winding, the wires 11, 12 undergo a heat treatment on the mandrel M to "set" them. While the prolonged heat treatment known in the tungsten metal wire art as "sintering" may be used in treating tungsten wire coils 11, 12, I have found it generally sufficient and preferable to use the less severe heat treatment known in the art as "annealing," since this removes most of the stresses due to wire drawing and coiling, yet leaves the wires 11, 12 ductile, and so reduces loss in handling and shipping coils and lamps. For annealing, the mandrel wire M with its coils 11, 12 may be run through an annealing furnace containing an atmosphere of hydrogen, thus cleaning and annealing it at one operation. No special precautions as to drying the hydrogen are ordinarily required. When the mandrel M is of molybdenum, a temperature of the order of about 1550° C. may be preferred, with an exposure of the windings thereto for a period of the order of 25 seconds, or not over half a minute. When the mandrel M is of iron or of mild, low-carbon steel, the temperature may be of the order of 1300° C., and should not substantially exceed this figure, in order to obviate alloying of iron with the tungsten of the windings 11, 12 which would embrittle the tungsten, while the exposure may be of the order of half that above indicated for a molybdenum mandrel. Even at 1300° C.,

too long an exposure of the tungsten windings 11, 12 in contact with an iron mandrel M may similarly embrittle the tungsten. After the heat treatment, the assembly of coils on mandrel is

5 cut to individual lengths and then the mandrel M is removed from within the windings 11, 12, which may readily be done by chemically disintegrating the mandrel, as by dissolving it out with any suitable reagent—such as the usual 10 combination of nitric and sulphuric acids for molybdenum, or hydrochloric acid for iron or mild steel.

In winding the wires 11, 12 on the mandrel M, they are highly stressed elastically, so that 15 they tend very strongly to uncoil. This elastic stress is largely relieved in the heat treatment, but not entirely so; hence when the wires 11, 12 are released and the mandrel M is dissolved out, the wires readjust themselves and are irregularly displaced.

The annealed coil assembly (of which only a fragment appears in Figs. 1-3) is cut into suitable lengths L which may be mounted in leadwire clamps 20, 20 of a fluorescent cathode mount 25 21, Fig. 4, according to the usual practice in mounting cathodes or filaments. As shown, the leads 20, 20 have the usual auxiliary anode extensions 22, 22 beyond the clamps. After mounting a coil L in lead clamps 20, 20, the latter may 30 be bent further apart somewhat, so as to stretch the coil L taut between them. This also has the effect of definitely separating the adjacent convolutions of the associated coils 11, 12 to a desired spacing. This completes the unactivated 35 cathode mount as shown in Fig. 4.

The impregnation of the coil with activating material may be carried out with the usual mixture of powdered alkaline earth metal carbonates in binder of nitrocellulose lacquer and diluent, 40 which may be applied with a "spoon" in the usual way to cover the coil and fill its interior and its interstices. To take full advantage of the large space afforded by and within the tubular basket or grillage formed by the coils 11, 12, the 45 liquid activating mix may be thicker than usual for coiled coil cathodes, about of the consistency of very thick cream; but care must be taken to avoid leaving an accumulation of this mix hanging to the exterior of the coil between the 50 leads 20, 20 or on the lead wire clamps. The resulting cathode mount is subsequently sealed into a fluorescent lamp tube, and is treated and activated as usual in the processing of the lamp to break the carbonates down to oxides.

55 In the impregnated cathode as shown in Fig. 5, none of the convolutions of either coil 11 or 12 are totally embedded in the activation material, which substantially fills the grillage formed by these coils, but only coats the outer sides of the

60 wires very lightly, as indicated by the stippling. After activation of the cathode shown in Fig. 5, that is, breaking down of the carbonates to oxides, the outer sides of the convolutions of coil 11 and the cross-over portions 15 of coil 12 have 65 a metallic luster. Thus the finer wire 12 heats up quickly and facilitates starting of the discharge, and the protruding bends of the wire 12 at its crossings 15 outside the wire 11 offer specially favorable points for the discharge to take off.

70 The contact or close proximity of the wires 11 and 12 at and adjacent the crossings 15 afford capillary grooves and corners that are favorable for retaining the activating material against positive ion bombardment. While the turns of 75 wire 12 are electrically in parallel with the wire

11 between adjacent crossings 15, and thus are similarly heated by current flow in the cathode, they are so short as to obviate overheating—either from by-current flow or by the discharge taking off from them—owing to the rapid conduction of heat along the wire convolutions 12 to the crossings 15.

For the assistance of those desiring to practice the invention, dimensions and other particulars for the fabrication of a cathode of a 40 watt fluorescent lamp operable on a voltage of 108 with a current of 0.41 ampere are here given, but are not to be understood as defining or limiting the invention:

For the mandrel M may be used round molybdenum or iron wire of 23 mil size, while for the wires 11, 12 may be used round tungsten wires of 2.3 and 0.7 mil sizes, both preferably what is known in the art as "non-sag wire." The primary, main conductor wire 11 of 2.3 mil size may be wound left-hand on the mandrel M at 172 turns per inch, while the secondary associated wire 12 of 0.7 mil size may be wound right-hand at 530 turns per inch. Using a length L of the resulting coil about 15 mm. long after heat treatment and removal of the mandrel M, it may be clamped in lead clamps 20, 20 with a length of 13 mm. of coil in circuit between them—comprising lengths of 174 mm. and 533 mm. respectively of the wires 11 and 12—and the clamps 20, 20 may then be bent apart to stretch this 13 mm. length to a length of 15 mm. in circuit between the clamps. The operations not here mentioned or described in detail may be performed as already described.

Fig. 6 illustrates a modification in which wires 11, 12 are wound on a mandrel M to equal but opposite pitches—one left-hand and the other right-hand, or vice versa. These pitches may be intermediate between those of the wire 11 and 12 in Figs. 1 and 2, so that the interval between adjacent turns 11, 12 shall be about the same, while the over-all length of the resulting cathode coil is correspondingly shorter. For a 40 watt 108 volt fluorescent lamp operating on 0.41 ampere, the mandrel wire M may be of 35 mil size, the wire 11 may be of 2.3 mil size and wound in a left-hand helix at 265 turns per inch, while the wire 12 may be of 1 mil size and wound right-hand at 265 turns per inch. The length of coil between the lead clamps 20, 20 (Fig. 4) may be 10.7 mm. and stretched to 11.5 mm.

Fig. 7 illustrates a modification in which the main heavier gauge conductor wire 11 is wound left-hand, a finer wire 12 is wound right-hand, and another finer wire 13 is wound left-hand.

In Fig. 8, the finer wire 12 is wound at less turns per inch and in the opposite direction from heavier wire 11.

In Fig. 9, two finer wires 12a, 12b are coiled side-by-side around the mandrel M and heavier wire coil 11.

In Fig. 10, the finer wire 12 is wound in the same direction as the heavier wire 11 but at less turns per inch.

What I claim as new and desire to secure by Letters Patent of the United States is:

1. A coiled filament comprising main helically coiled conductor wire; associated finer wire helically coiled substantially coaxially and coordinately with said conductor wire, with portions of its convolutions crossing over and other portions intervening in the space between convolutions of said conductor wire and interlocked therewith against relative displacement of the coils.

2. A filamentary cathode comprising main helically coiled conductor wire; associated finer wire helically coiled substantially coaxially and coordinately with said conductor wire, and having portions of its convolutions crossing over and other portions intervening in the space between convolutions of said conductor wire, whereby the coils are interlocked against relative displacement; and electron-emissive-activating material held in the openwork tubular grill cooperatively formed by the coordinate convolutions of said wires.
3. A coiled filament comprising main helically coiled conductor wire; associated finer wire helically coiled substantially coaxially and coordinately with said conductor wire but to a different pitch, with portions of its convolutions intervening in the space between those of said conductor wire and other portions of its convolutions crossing the latter in bends outside of and conformable thereto.
4. A coiled filament comprising a single main conductor wire helix; a single associated finer wire helically coiled to a coil of different degree of and opposite pitch coaxial and coordinate with said conductor wire, and having portions of its convolutions intervening in the space between convolutions of the conductor wire and other portions crossing the latter in bends outside of and conformable thereto.
5. A filamentary cathode comprising a single main conductor wire helix; a single associated finer wire helically coiled to a coil of the same pitch but opposite helical sense coaxial and coordinate with said conductor wire, with its convolutions intervening between and crossing those of the conductor wire in bends outside of and conformable thereto, and electron-emissive-activating material held in the openwork tubular grill co-operatively formed by the coordinate convolutions of said wires.
6. A coiled filament comprising main helically coiled conductor wire; associated finer wire helically coiled substantially coaxially and coordinately with said conductor wire in the same helical sense but to a different pitch, with convolutions intervening between those of said conductor wire and also crossing the latter in bends outside of and conformable thereto.
7. A method for fabricating a complex filamentary coil which comprises helically winding elastic main conductor wire on a mandrel, with its adjacent convolutions separated, and helically winding finer wire on said mandrel with convolutions of the finer wire lying between and crossing over those of the conductor wire, and subsequently removing the mandrel and permitting the convolutions of main conductor wire to open up, whereby the coils are interlocked against relative displacement.
8. A method for fabricating a complex filamentary coil which comprises helically winding elastic main conductor wire on a mandrel, with its adjacent convolutions separated, and helically winding finer wire on said mandrel to an opposite pitch, with convolutions of the latter wire lying between and crossing over those of the conductor wire.
9. A method for fabricating a complex filamentary coil which comprises helically winding elastic main conductor wire on a mandrel, with its adjacent convolutions separated and elastically stressed, helically winding finer wire on said mandrel with convolutions of the latter wire lying between and crossing over those of the conductor

wire, partially relieving the elastic stress in said main conductor wire, and releasing said coiled wires and removing said mandrel from the coils.

10. A method of fabricating a complex filamentary coil which comprises continuously winding a main conductor wire on a long length of mandrel with its adjacent convolutions separated and elastically stressed, continuously winding finer wire under tension over said main conductor wire with convolutions of the finer wire crossing over those of the conductor wire and contacting the mandrel between convolutions of the conductor wire, cutting the resultant assembly to individual filament lengths, and then removing the mandrels from the individual filaments.

11. A method for fabricating a complex filamentary coil which comprises helically winding elastic main conductor wire on a mandrel, with its adjacent convolutions separated, helically winding finer wire on said mandrel in the opposite helical sense and at more turns per inch than the main conductor wire, with convolutions

of the finer wire crossing over those of the main conductor wire and contacting the mandrel between convolutions of the main conductor wire, and subsequently removing the mandrel and permitting the convolutions of main conductor wire to open up, whereby the coils are interlocked against relative displacement.

12. A filamentary cathode comprising main helically coiled conductor wire; associated finer wire helically coiled substantially coaxially and coordinately with said conductor wire but in the opposite helical sense and at several-fold the number of turns per inch, with portions of its convolutions crossing over and other portions intervening in the space between and within the convolutions of said conductor wire and interlocked therewith against relative displacement of the coils; and electron-emissive activating material held in the tubular grill cooperatively formed by the co-ordinate convolutions of said wires.

WILLIAM P. ZABEL.
